MASSAGING DEVICE

Joseph D. Bell, San Francisco, Calif.; Pearl B. Bell, administratrix of said Joseph D. Bell, deceased

Application January 3, 1950, Serial No. 136,514

12 Claims. (Cl. 128—57)

1

The present invention relates to improvements in a massaging device and its principal object is to provide a massaging device in the form of a mat having a plurality of elongated massaging elements arranged in parallel relation and having means for imparting massaging motion to the said elements.

A further object of the invention is to provide a mat of the character described which may be used as a portable unit for application to the human body or any part thereof, while the latter is in upright or seated or any other desired position, but which may also be bodily incorporated in a frame structure provided with suitable means for operating the massaging elements by hand or by use of power.

More particularly it is proposed to provide a mat comprising a plurality of rockable massaging elements suitably interlocked to form a chain, the elements being interconnected by suitable drive means whereby rocking motion imparted to one of them will be transmitted to others for synchronous motion.

It is further proposed to provide suitable means for attaching the mat to any desired portion of the human body.

It is further contemplated to provide one or more operating handles for individual massaging elements allowing the user to rock the elements back and forth over the body while the mat is attached thereto.

It is further proposed in the preferred form of the invention to arrange the massaging elements in two separate series and to arrange the operating means in such a manner that the elements of the two series are rocked in opposite directions to provide massaging motion from opposite sides to and away from a common center.

It is additionally proposed to provide a frame structure including a pair of elastic tracks on which the massaging mat may be bodily supported, and provided with means for imparting massaging motion to the different elements of the mat.

It is further proposed to arrange the tracks in such a manner that the mat may be removed therefrom for use as a portable unit and that the tracks may be removed with the mat to again form a portable unit in which the tracks are used to prevent buckling of the mat.

And finally, it is proposed to provide operating means for the massaging mat within the frame structure, the parts being arranged in such a manner that the same handles used for operating the massaging elements in the portable unit

2

are also employed for the driving means to operate on.

Further objects and advantages of my invention will appear as the specification proceeds, and the novel features of my invention will be fully defined in the claims attached hereto.

The preferred form of my invention is illustrated in the accompanying drawings, in which Figure 1 shows an end view of my massaging device,

Figure 2, a top plan view of the same,

Figure 3, a detail view of the mat as applied to a human figure,

Figure 4, a perspective view of the frame on which the mat may be detachably supported, and

Figure 5, a detail view of a modified form of massaging element used in my device.

While I have shown only the preferred form of my invention, I wish to have it understood that various changes and modifications may be made within the scope of the claims attached hereto without departing from the spirit of the invention.

Referring to the drawing in detail, my massaging device comprises in its principal features a mat 1 and a frame structure 2.

The mat is here shown as consisting of a plurality of rollers 3 arranged in parallel relation, each of the rollers having short shafts 4 projecting from opposite ends thereof and links 5 connecting the shafts at opposite ends of the mat.

Each roller also carries a gear wheel 6 and each of the connecting links carries an idler gear wheel 7 meshing with the former gear wheels so that upon a rocking motion imparted to one of the rollers the others will rock in synchronism.

While all the rollers may thus be made to rock in the same direction, I prefer to make the mat in two sections symmetric on opposite sides of the center line, with the idler gear between the rollers adjacent the center line omitted. This allows the rollers of one section to be operated independently of those of the other section, and in my preferred form I cause the rollers to be rocked back and forth in opposite directions by means of two handles 8 projecting from the outer rollers.

These handles are preferably made U-shaped, as shown in Figure 3, and are made to project outwardly when the inner face of the mat is placed against a portion of the human body, so that the person using the mat may rock the outer rollers in opposite directions, this motion being transmitted to the inner rollers on each side of the center line by the gear wheels and idlers hereinafter described.

3

The mat may be held to the body by means of suitable straps 9 which may be secured to the end connecting links on one side of the mat and fastenable to the end connecting links on the opposite side as shown at 10. Shoulder straps 9' may also be provided in the manner shown.

Thus the rollers may be made to massage the underlying area of the human body by crowding portions of the surface layer of the body first toward the center line and then away from the center line in a rocking motion. It will be understood that the rollers may be made of any suitable shape adapted for massaging action, either in the form of cylinders, as shown, with rubber surfaces, or of semi-cylinders, or mere massaging strips, it being understood that the rollers do not roll back and forth along the body but merely rock on their own axis, while the mat as a whole remains substantially stationary.

If it is desired, selected rollers, or all of them, may also be suitably contoured in their outer surfaces to produce a compound kneading action, as shown, for instance at 3' in Figure 5, in which the surface of the roller is formed with reverse threads as at 11 which combine upward and downward push of the surface layer with the sideways push of the plain roller.

The massaging action can further be stimulated by introducing additional massaging elements between selected elements such as the 30 massaging strips 12 which are supported by the idler gears 7, with their free edges projecting into the inner plane of the mat, as shown in Figure 1. These strips will rock in a direction opposite to that of the adjacent rollers and will produce local massaging effects in addition to the general massaging effect produced by the main rollers.

The mat thus far described may be used as a portable unit and may be readily applied to any suitable part of the human body and may be operated by the user, thus involving a certain amount of exercise on the part of the user.

But, the mat may also be used as part of a frame structure shown in detail in Figure 4 in case the user desires to lie down on the mat and to massage himself while relaxing on the mat.

The frame structure, shown at 2, comprises a rectangular bottom frame 13, posts 14 rising from the four corners thereof, and two elastic tracks 15 removably secured upon opposing pairs of posts in parallel relation. These tracks are made of springy material and may have central coiled springs 16 incorporated therein. They are secured upon the posts by means of screws 17.

The mat may be placed on these tracks in the manner shown in Figures 1 and 2, with the projecting shafts 4 resting on the tracks, and the mat as a whole is held against movement on the tracks by suitable end stops 18 which are bent to project over the end shafts in the manner shown. Since the mat as a whole is free to buckle, due to the link connection, the end shafts may be easily withdrawn from the stops 18 for removal of the mat. On the other hand, the tracks may be disconnected from the frame by removal of the screws 17 and may be moved with the mat to form a unitary structure therewith for use as illustrated in Figure 3, in case it is desired to prevent buckling of the portable unit and to apply more uniform pressure upon the body, it being understood, of course, that the tracks would lie upon the outer faces of the shafts 4.

When the mat is arranged to lie on the frame, the U-shaped handles 8 project straight downward, as shown in Figure 1, and may be operated

4

for producing massaging action in any suitable manner.

One means of operating the handles is shown as comprising a main shaft 20 revolvably mounted in the brackets 21 to lie transversely underneath the mat, and operable for rotary movement by means of a crank handle 22 or by any suitable power means, such as an electric motor. This shaft carries a cam 23 in the form of a disc inclined with respect to the shaft.

Two side shafts 24 are mounted on opposite sides of the main shaft and each of the side shafts carries a slideable tube 25 held against rotary motion in any suitable manner, as by pins 26 riding in a slot 27. One of the tubes has a pin 28 riding on one face of the cam for operation by the latter against a coiled spring 29, which urges the sleeve into the opposite direction, while the other tube has a pin 30 riding on the other face of the cam for operation by the latter against a coiled spring 30' encircling the shaft 24.

Thus it will be seen that when the cam is made to rotate, manually or by a motor, the two tubes will be made to travel back and forth on their respective shafts in opposite directions. The two tubes are connected to the handles 8 by means of links 31 and thus cause the handles to rock back and forth for operating the mat rollers in the manner previously described.

Another form of operating the handles is by means of cords 32 attached to the handles as at 33 and guided over pulleys 34 suitably supported in the sides of the frame structure. These cords may be operated by means of hand holds 35 by a person lying on the mat, this operation being also against the springs 29 and 30' respectively which insure return movement.

Thus a person lying on the mat can operate the handles 8 for massaging action by operation of the cord or by operation of the cam shaft, neither one of which interferes with the other.

Since the entire frame structure is comparatively light in weight, it is entirely feasible for the user to use the entire structure in the manner shown in Figure 3. In case the operator desires to use the entire device as a portable unit he may fasten the same upon the body by suitable straps fastened in hooks 36 secured upon the frame.

I claim:

50. 1. In a massaging device, a main frame having spaced elastic tracks thereon, a massaging mat including a series of elongated rocking elements having their ends supported on the tracks and linkage connecting the rocking elements, and means for imparting rocking motion to said elements.

55. 2. In a massaging device, a main frame having spaced elastic tracks thereon, a massaging mat supported on the tracks and including a series of elongated rocking elements, linkage connecting the rocking elements and gear drives between the latter, and means operative on the gear drives for imparting synchronized rocking motion to the said elements.

60. 3. In a massaging device, a main frame having spaced elastic tracks thereon, a massaging mat supported on the tracks and including a series of elongated rocking elements, linkage connecting the rocking elements and gear drives between the latter, and means operative on the gear drives for imparting synchronized rocking motion to the said elements, the mat being made to rest loosely on the tracks and being separable from the motion imparting means so as to allow the mat

to be lifted from the tracks as a unitary structure.

4. In a massaging device, a main frame having spaced elastic tracks thereon, a massaging mat supported on the tracks and including a series of elongated rocking elements, linkage connecting the rocking elements and gear drives between the latter, and means operative on the gear drives for imparting synchronized rocking motion to the said elements, the tracks having stop members thereon to prevent travelling of the mat on the tracks.

5. In a massaging device, a massaging mat comprising a series of elongated rocking elements arranged in parallel relation, links interconnecting the rocking elements, a gear wheel on each of the elements and idler gears interposed between the gear wheels and carried by the links, means for supporting the mat in elevated position, and means for imparting rocking motion to one of the elements whereby other rocking elements are rocked in unison, the latter means comprising an arm projecting from said element, a drive shaft having a cam thereon and a driving connection between the cam and the arm.

6. In a massaging device, a massaging mat comprising a series of elongated rocking elements arranged in parallel relation, links interconnecting the rocking elements, a gear wheel on each of the elements and idler gears interposed between the gear wheels and carried by the links, means for supporting the mat in elevated position, and means for imparting rocking motion to one of the elements whereby other rocking elements are rocked in unison, the latter means comprising an arm projecting from said element, pulleys mounted on opposite sides of the arms, and cords secured upon the arm and guided over the pulleys for manual operation.

7. In a massaging device, a main frame having a pair of elastic tracks thereon, a bodily detachable, flexible massaging mat supported on the tracks, the mat comprising a plurality of elongated rockable members chained together with gear connections between the members, a cam and means for operating the same, and a driving connection between the cam and one of the members for rocking other rockable members in unison.

8. In a massaging device, a main frame, a massaging unit supported thereon, said unit comprising a plurality of massaging rollers and links pivotally connecting the rollers at opposite ends thereof with freedom of rocking action of each of said rollers, a cam mounted on the frame, and means operable by the cam and connected to the unit to impart said action, and the unit being separable from the frame for independent use.

9. In a massaging device, a main frame, a massaging unit supported thereon, said unit comprising a plurality of massaging rollers and links pivotally connecting the rollers at opposite ends

thereof with freedom of rocking action of each of said rollers, a cam mounted on the frame, and connecting means between the cam and the unit operable for imparting said action, the said connecting means being separable to allow the unit to be removed for independent use and including a handle on the unit operable to impart said action when the unit is used independently of the frame.

10. A massaging device comprising a flexible mat comprising a plurality of massaging rollers, links pivotally connecting the rollers at opposite ends with freedom of rocking motion of each of said rollers, means for securing the mat upon a human body, a handle projecting from one of the rollers whereby the latter may be rocked for massaging action, and drive means between said roller and other rollers whereby the other rollers are rocked in unison with the first roller.

11. A massaging device comprising a flexible mat comprising a plurality of massaging rollers, links pivotally connecting the rollers at opposite ends with freedom of rocking motion of each of said rollers, means for securing the mat upon a human body, handles projecting outwardly from the two outer rollers whereby the latter may be rocked for massaging action, and drive means between the outer rollers and adjacent intermediate rollers whereby the intermediate rollers are rocked in unison with the outer rollers.

12. In a massaging device, a massaging mat comprising a series of massaging rollers arranged in parallel relation, links pivotally connecting the rollers at opposite ends thereof, driving connections between the rollers, means for supporting the mat in elevated position with respect to a floor surface, and means for imparting rocking motion to one of the rollers whereby other rollers are moved in unison, the latter means comprising an arm projecting from said roller, a pulley and a cord secured upon the arm and guided over the pulley for manual operation.
